UNITED STATES PATENT OFFICE.

THOMAS E. MURRAY, OF BROOKLYN, NEW YORK.

RADIATOR.

Original application filed April 26, 1924, Serial No. 709,080. Divided and this application filed July 21, 1928. Serial No. 294,364.

In a previous application No. 709,080, filed April 26th, 1924, I have covered certain improvements in radiators for heating the air of rooms having a heating element and certain plates applied thereto for providing a greatly extended heating surface in contact with the air; the heating element being a tube for steam or hot water or other fluid (or for cold brine or the like when the 10 radiator is used to cool the air) or being an electric or other style of heating element. The present application is a division thereof covering one of the several types illustrated in the parent application. The single figure 15 of the drawing illustrates in perspective view the principal parts of the improved radiator.

Referring to the drawings, 1 is a vertical tubular casing or conduit for the heating 20 (or cooling) medium, the upper portion of which is surrounded by an extended surface structure, while the lower end 2 is left circular for mounting connections of any desired sort.

25 A sheet of metal providing a greatly extended area is provided around and in close contact with the heating element or casing 1. The latter is preferably of copper for the best conductivity. The sheet metal also 30 is preferably of copper. It can be made very thin because of its high conductivity and because of its shape which contributes greatly to its lateral stiffness and in fact to the stiffness of the entire structure. It 35 is bent horizontally to form a number of hollow flues which are closed in horizontal section and open only at the top and bottom and are of considerable height so as to induce a strong upward draft of the air as the latter is heated. The extended area structure is of special shape to secure the best 40 results.

45 The hollow fins or closed flues are separated by portions 3 of sufficient width to secure a good conducting contact with the heating element or casing 1. The portions 3 are shaped to fit the casing closely and are united thereto by heat and pressure as, for example, by soldering, welding, or brazing. Such unions make a continuous metallic union which is the best for heat transfer, but other methods of securing the parts 50 together may be used.

55 The space between the hollow fins is left just sufficient for introducing the necessary

tubes to form the desired union with the central casing, and the fins themselves are made of a special shape to secure the best flue effect. The sides of the flues are made of two parts 4 and 5, the latter converging to 60 a point or edge 6. A large number of these flues are mounted around the circumference of the tube so as to secure the maximum area, and consequently each flue is narrow in the cross-section. But within these limits 65 the flues are made of maximum width in portions closely adjacent to the central casing by extending the opposite portions 4 of each flue in directions at least parallel to and preferably slightly diverging from each other, and then bending the sheet to form the converging portions 5. Thus the greater 70 volume of air passing up the flue is in contact with the heat transferring area which is fairly close to the central heating element, and the latter commence to converge only at a point comparatively remote from the heating element, so that the sides are convexed 75 outward at an intermediate point.

80 The fittings for connecting the central casing or tube with the inlet and outlet pipes are not illustrated. They may be of any usual or suitable design. The extended area structure may be made of a single sheet or 85 of single sheets welded at their edges to one another or to the central casing.

90 The inner portion 3 of this structure is preferably symmetrical in cross-section and extends the full length of the sheet so as to secure the maximum contact area with the casing 1 for conduction of heat very rapidly 95 to the portions 4 and 5. The air is heated by contact with the latter, both within the flues and within the space between adjacent flues. The heat radiating effect of the complete apparatus is small compared with the convection effected; that is, the heating of 100 or by contact with the extended surfaces and the rapid upward movement of such heated air causes its circulation through the room. The fact that the heating element 1 forms the inner wall of each of the flues adds materially to the heating effect within such flue. The rapid draft and circulation 105 of the air takes the heat rapidly away from the central heating element and effects a correspondingly rapid movement of the steam or other heating medium. Thus a high temperature heating medium may be 110 used with efficiency and the entire radiator

may be very much smaller than the ordinary cast iron radiators commonly used, for the same duty. To the same end of securing a small radiator for performing a large duty 5 it is preferable to use for both heating element and the extended area structure metal of high conducting qualities such as copper, in which term I include brass and other cuprous alloys. But the structure is advantageous with other metals.

For high temperature steam or other high temperature heating elements, the casing 1 is preferably comparatively small in width or diameter, and the heat transferring structure extends outward to a distance substantially greater than the width of the central element. Such an extension of the corrugations adds lateral stiffness to the structure and contributes to the chief purpose of 15 the invention, the heating of and rapid circulation of a comparatively large volume of air from a comparatively small heating element operated at a high temperature, so that the comparatively small radiator will 20 perform the same duty for which much larger radiators are now generally used.

Other modifications may be made by those

skilled in the art without departing from the invention as defined in the following claim.

What I claim is:

A radiator including in combination a central vertical casing and a heat transferring structure surrounding the same comprising a sheet corrugated in horizontal section and having portions in close contact with the central casing and making a good heat conducting joint therewith and forming vertical flues for inducing a rapid upward draft of the heated air, said casing being of comparatively small cross-section and said heat transferring structure extending outward to a distance substantially greater than the width of the casing, so that the latter may carry a high temperature 40 heat medium and the heat therefrom will be taken away and transferred to the air and carried off by the rapid draft induced in the flues, the parts being of copper to further facilitate the rapid transfer of heat 45 to the extreme limits of the structure.

In witness whereof, I have hereunto signed my name.

THOMAS E. MURRAY.
